CHLORINATING UNIT

Albert L. Eisenman, Dallas, Tex.

Application June 19, 1947, Serial No. 755,777

3 Claims. (Cl. 210—28)

1

This invention relates to new and useful improvements in chlorinating units.

The invention has particularly to do with water chlorinating units for water treating systems and the like.

One object of the invention is to provide a chlorinating unit including, a simple by-pass adapted to be connected in the water supply line and an improved aspirator arranged in the by-pass and utilizing water velocity to inject the treating chemical in the water flowing through the by-pass, whereby a chlorinating solution may be introduced into a water supply line in an efficient and reliable manner.

A further object of the invention is to provide a chlorinating unit operated entirely by water pressure and which is easy to install and low in maintenance cost.

Another object of the invention is to provide an improved aspirator including, a water injector, a chemical pick-up conductor and a visual gauge for observing the aspirator pressure, together with means for regulating the rate of chemical injection and check means for preventing back flow of water into the chemical source when the unit is idle.

Still another object of the invention is to provide an improved chlorinating unit which is automatic in operation and normally carries out its chlorinating function only when water is being drawn from the water system to which the unit is connected.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is an elevation of a unit constructed in accordance with the invention,

Fig. 2 is a perspective view of an aspirator constructed in accordance with the invention,

Fig. 3 is a transverse vertical sectional view of the aspirator,

Fig. 4 is a similar view at right angles to Fig. 3,

Fig. 5 is a horizontal cross-sectional view of the aspirator, and

Fig. 6 is a view of the chemical foot valve, partly in elevation and partly in section.

In the drawings, the numeral 10 designates a water supply pipe which may lead from a water well or other source of water supply. This pipe is connected to the intake of a centrifugal or any

2

other suitable type of pump 11 which is horizontally disposed and driven by an electric motor 12, the details of the pump and motor being immaterial. A discharge pipe 13 leads from the pump to a storage or accumulating tank 14, from which a service pipe 15 extends in the usual manner.

While the invention is illustrated and described with respect to use with a pump and accumulator tank unit, it obviously may be equally well employed with any conductor of fluid under pressure or any type of water system. Thus, it may be employed in conjunction with an ordinary water supply pipe through which water flows under pressure. In the latter instance, a pressure reducing means in the supply pipe is usually necessary.

A short riser pipe 16 leads from the outlet 17 of the pump and constitutes the first part of a by-pass line, indicated generally by the letter A. The riser is connected in the bottom of a manifold 18, which carries a pressure gauge 19 indicating the pressure within the water system. A lateral pipe 20 extends from the manifold to a strainer 21. A tubular conductor or a pipe 22 extends from the strainer to one side of an aspirator or injector, indicated generally by the letter B, while a conductor or a pipe 23 extends from the opposite side of the aspirator to the intake side of the pump 11. The conductors 22 and 23 and the aspirator constitute the by-pass. A tubular conductor or a pipe 24 extends from the bottom of the aspirator down into a chemical receptacle 25 and has a foot valve 26 on its lower end. The tubular conductors 22, 23 and 24 are preferably flexible, being made of material such as rubber or plastic hose.

In general, the pump 11 supplies water from the pipe 10 to the tank 14 by way of the pipe 13. A portion of the water (under pressure) is bypassed through the riser 16 and lateral 20 to the conductor 22, being cleaned when passing through the strainer 21. The by-passed water in passing through the aspirator creates a sufficient suction to pick up the chemical from the receptacle by way of the conductor 24, whereby the chemical is admixed or dissolved in the water and discharged by way of the conductor 23 into the pump 11. The pressure and velocity of the bypassed water are the sole means for supplying and injecting the chemical or chlorinating solution into the water supply line.

The aspirator B includes a block or cubical housing 27 which has a flow passage 28, extending transversely therethrough. Annular recesses 29

surround the ends of the passage and the end

portions of the passage are provided with screw threads 29. An injector nozzle 30 has a reduced, externally screw-threaded nipple 31 which is screwed into the threads 29 at one end of the passage; while an injector nozzle 32 has a reduced, externally screw-threaded nipple 33 screwed into the threads 29 at the opposite end of said passage. Each nozzle has an annular shoulder 34, located in the adjacent recess and bearing against a gasket 35, seated in the recess.

The nozzles have serrated shanks 36 at their outer ends, on which the ends of the flexible conductors 22 and 23 may be engaged. The injector nozzle 30 has an axial bore 37 extending inwardly to a reduced bore or duct 38 extending through the nipple 31. The nipple 33 of the injector nozzle 32 has a reduced bore or duct 39 extending outwardly to a counterbore 40. The passage 28 is located just above the center of the block 27 (Figs. 3 and 4), and bisects a vertical, cylindrical chamber 41. The nipple 31 has a truncated tip 31' extending into the chamber, diametrically opposite, but spaced from, a conical sump 33' in the nipple 33, which also extends into the chamber. By this arrangement the ducts 38 and 39 are axially aligned with a short gap therebetween.

At the bottom of the chamber 41, an inclined annular seat 42 surrounds a short vertical duct 43. A check valve 44 engaging in the seat has its reduced stem 45 loosely depending into the duct. The duct opens at its lower end into a horizontal bore 46, at right angles to the passage 28. At the inner end of the bore an inclined annular seat 47 is formed and a reduced bore 48 extends from the seat. A needle valve 49, of less diameter than the bore 46, extends axially of said bore and has its needle 50 extending through the seat 47 into the reduced bore 48, for regulating flow from the bore 48 to the bore 46. The stem of the needle has a snug turning fit in a packing 51, countersunk in the block 27 and confined by a gland nut 52, screwed into the block in the usual manner.

A nipple 53 is screwed into a screw-threaded sump 54 in the bottom of the block 27. The upper end of the conductor 24 is fastened on the nipple and the nipple has an axial bore 55 which registers with a port 56 in the under side of the bore 48. The lower end of the conductor 24 is suitably fastened on the foot valve 26, which is best shown in Fig. 6.

The foot valve has a central well 57, from the bottom of which ducts 58 extend radially to the outer surface of the valve body. An internally screw-threaded counterbore 59 is provided at the upper end of the well, with an inclined annular seat 60 therebetween. A check valve 61 engages on said seat. A nipple 62 is screwed into the counterbore and is secured in the lower end of the conductor 24. It will be seen that when the unit is idle, the upper check valve 44 at the bottom of the chamber 41 will be closed, thus preventing liquids from flowing into the duct 43 and thence to the conductor 24; while the check valve 61 in the foot valve will close and trap liquids between the check valves.

Although a variety of chemicals or chemical solutions may be added to a water stream by the utilization of this invention, it is concerned primarily with the chlorination of water. Due to the corrosive nature of chlorinating agents, it is desirable that the aspirator and foot valve, along with the other portions of the system which come in contact with relatively strong treating

chemicals such as chlorine, be formed of a material resistant to such corrosion. Hard rubber and various synthetic resins have been found quite suitable for this purpose although other materials, resistant to the particular chemicals being handled, may be used to advantage.

In addition, various types of conductors and means for connecting said conductors to the various elements of the invention may be employed. The hose and nipple structure described may obviously be replaced with other types of connections.

Due to the turbulence within the chamber 41 when the unit is started in operation, water will fill the chamber 41, after unseating the valve 44. This water will displace the air in and will rise into the restricted axial well 63, extending vertically in a cylindrical transparent gauge 64. This gauge is preferably made of a clear hard plastic and has a reduced, screw-threaded stem 65 at its lower end screwed into the upper end of the chamber. A packing gasket 66 is partially countersunk in the top of the block 27 and is engaged by the gauge to provide an airtight connection.

Substantially all of the air trapped in the well 63 will be removed through the turbulence and aspirating action set up in the chamber 41, so that water will rise nearly to the top of the well 63 under the pressure existing in the water system. However, as soon as the injection action is started by starting of the pump 11 and the consequent suction created, the water column in the well will be lowered because of the reduced pressure in the chamber 41. In order to indicate the proper or recommended degree of suction exerted within the chamber 41, an external annular groove 67 is formed in the surface of the gauge to indicate the proper height of the water column therein. As an illustration, if it is desired to operate the unit at the equivalent of 15 inches of mercury, absolute pressure, the groove is located at the level the water column in the well 63 will assume under such conditions. Since the gauge is transparent, the height of the water column may be observed therethrough.

The use of this simple pressure gauge eliminates the expense of a complex gauge of the usual variety, and, in addition, provides a rugged gauge not damaged by relatively large pressure changes.

In order that test-tube observations as to the chemical content of the treated water may be readily made, I provide vertical bores 68, 69 and 70 in the front side of the block 27. An arcuate recess 71 is formed in the face 72 of the block which exposes the front portions of the bores. In the central bore a test tube 73 may be inserted, while tubes 74 and 75 may be inserted in the bores 68 and 70, respectively, on each side thereof. Specimen solutions are placed in the tubes 74 and 75 and may be sealed therein, such solutions representing samples of water with a minimum and a maximum chemical content. As an illustration, the solution in tube 74 may contain the minimum recommended percentage of chlorine with a suitable colorimetric indicator such as orthotolidine added thereto; while the specimen solution in tube 75 may represent the maximum recommended percentage. The tube 73 may be removed, filled with water from the pipe 15 and then, after addition of a colorimetric indicator or reagent, inserted in the bore 69, whereby a comparison with the specimen solutions in the tubes 74 and 75 may be made.

The operation of the unit is very simple. When

the pump 11 is placed in operation, the major portion of the water is discharged through the pipe 13 into the tank 14. A portion of the discharged water is by-passed to the conductor 22 by way of the connections 16, 18 and 20 and cleaned through the strainer 21. This by-passed water is usually under a pressure of 40 to 50 pounds per square inch, but the pressure may vary or be adjusted.

The water enters the bore 37 of the injector nozzle 30 and flows through the reduced duct 38, whereby a high velocity jet is produced and directed across the chamber 41 into the sump 33' and thence into the reduced duct 39. The jetting action of the water across the chamber creates a suction which lifts the check valve 44 and draws the liquid chemicals or chlorinating liquid through the passages 43, 46, 48, 55, and 56 from the conductor 24. The suction also unseats the check valve 61 and draws in the chlorinating liquid through the ducts to the well 57. The chlorinating liquid drawn into the chamber 41 is picked up by the water jet and carried into the duct 39 of the ejector nozzle 32, whereby a chlorinating solution is formed. This solution is conducted by way of the bore 40 and conductor 23 to the intake of the pump 11.

It will be noted that the device is automatic in its operation. The flow through the aspirator unit occurs only when water is flowing through the conductor to which the invention is applied. Thus, when no flow exists, this chlorinating unit is idle. But, as soon as a flow of water commences, the chlorinating action is resumed so that the device operates only when water is being drawn from a water system.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. In a fluid treating system characterized by a pump having an intake connected to a fluid source and a discharge with a discharge conductor for supplying fluid under pressure extending from said discharge, a fluid treating unit including a by-pass conductor connected into said discharge conductor for by-passing a portion of the fluid therefrom, an injector having inlet, outlet and suction openings with its inlet opening connected to said by-pass conductor, a source of treating liquid supply, a liquid con-

ductor leading from said liquid supply to the suction opening of said injector, and a second by-pass conductor leading from the outlet opening of said injector to the intake of the pump for conveying a treated solution from the injector to the intake of said pump.

2. In a fluid treating system, a first conductor for conveying fluid under pressure, means to produce a pressure differential in said conductor, a fluid treating unit including a by-pass conductor connected at one end to said first conductor on the high pressure side of said pressure differential means for by-passing a portion of the fluid therefrom, an injector having inlet, outlet and suction openings with its inlet opening connected to the other end of said by-pass conductor, a source of treating liquid supply, a liquid conductor leading from said liquid supply to the suction opening of said injector, and a second by-pass conductor leading from the outlet end of said injector to said first conductor on the low pressure side of said pressure differential means for conveying a treated solution from the injector to said first conductor.
3. A fluid treating unit for a fluid supply line including, a treating liquid receptacle, an injector having a suction inlet, a liquid conductor leading from said receptacle to said suction inlet, said supply line having means to produce a pressure differential therein, an injector nozzle in said injector, a fluid conductor leading from said supply line on the high pressure side of said pressure differential means to said injector nozzle, an ejector nozzle in the injector and aligned with the injector nozzle, and a fluid conductor leading from the ejector nozzle to the supply line on the low pressure side of said pressure differential means.
